INVENTOR.

Michael J. O'Connor

UNITED STATES PATENT OFFICE.

MICHAEL J. O'CONNOR, OF LOUISVILLE, KENTUCKY.

MACHINE FOR CHANNELING ROCK FOR GRINDSTONES, &c.

SPECIFICATION forming part of Letters Patent No. 307,792, dated November 11, 1884.

Application filed July 30, 1884. (No model.)

To all whom it may concern:

Be it known that I, MICHAEL J. O'CONNOR, a citizen of the United States, residing at Louisville, in the county of Jefferson and State 5 of Kentucky, have invented certain new and useful Improvements in Machines for Channeling Rock for Grindstones, &c.; and I hereby declare the following to be a full, clear, and exact description of the same, reference 10 being had to the accompanying drawings, in which—

Figure 1 is an elevation of a machine embodying my invention. Fig. 2 is a plan view, partly in section, of the revolving tool-arm 15 and mechanism for actuating the same. Fig. 3 is a top view of the adjustable base for column A. Fig. 4 is an enlarged detail view of the shaft *g* in section, loose pulley *G*, and clutch mechanism for causing the shaft *g* to 20 rotate with the pulley when the drill rises.

Like letters refer to like parts wherever they occur.

My invention relates to the construction of apparatus for channeling and quarrying grind- 25 stone and other circular-shaped stone out of the solid rock.

Heretofore, so far as I am aware, it has been the general practice to quarry the stone in irregular blocks, and then to reduce them to 30 the proper or desired form by picking, spalling, and scabbling. Such a procedure necessitates considerable labor and results in great waste of material, all of which it is the purpose of the present invention to avoid.

To this end the main feature of the invention 35 consists in mounting the channeling-tool or drill upon a revolving arm, which arm rotates around a fixed axis, column, or post, so as to cause the tool to describe a circle while operating, thus quarrying the block in its ultimate form.

A second feature of the invention consists 40 in actuating the rotating arm or tool-carrier from the drill, so that its movement will alter- 45 nate with and be controlled by the drill, and the machinery be thus relieved from any strain consequent on the irregular action of either the arm or drill.

There are other minor points of novelty 50 which will hereinafter more fully appear.

I will now proceed to describe my inven-

tion more specifically, so that others skilled in the art to which it appertains may apply the same.

In the drawings, A indicates a column, post, 55 or center support for the drill or channeler, provided with a base or platform, Y, to which it is secured, being strengthened by ribs, as at *y*, if desired. The column A extends through the base Y, and terminates in a rectangular 60 foot, *a*, by means of which (and wedges or equivalent devices) it is anchored to the rock when in operation.

Projecting through the base Y are screws S 65 S, by means of which the base and column may be adjusted, and pivoted to the column A are extension or sliding legs L L, which brace and stiffen the column A when properly adjusted.

Secured to the column A is a gear or worm 70 wheel, I, the object of which will hereinafter appear.

B indicates a revolving arm or tool-carrier journaled on the post or column A just over the gear or worm wheel I, and projecting at 75 right angles thereto, which arm supports the channeler or drill C.

The channeler or drill C, being no part of the present invention, may be of any approved form. 80

The drill, whatever its character, should be so connected with the arm B, as at *b*, or otherwise, that it can be moved along the arm to and from the column A to increase or decrease the diameter of the stone to be quarried. At- 85 tached to the piston of the drill is the vertical rod D, having an eye, *d*, at each end, for securing the ends of a cord or band, E, which cord or band passes over guide-pulleys F and around a power-pulley, G. The power-pulley G is journaled loosely on a shaft, *g*, which shaft is in turn journaled on the arm B, and provided with a worm or screw, H, which engages with the gear or worm wheel I, attached to the column A. The loose pulley G is pro- 90 vided with a clutch so arranged that when the pulley is rotated by the rise of the drill-piston it clutches the shaft *g* and causes it and the worm or screw H to rotate with it, while in the reverse rotation of the pulley G it moves 95 loosely on the shaft *g*, and the shaft *g* can be held by a reverse clutch, if desired. 100

The construction being of the general character hereinbefore specified, the machine will be operated as follows: A square or rectangular hole, *v*, is formed in the rock *R* to be quarried. The rectangular foot *a* is placed therein and tightly wedged therein by means of wedges *w*, the machine properly adjusted by means of the set-screws *S S*, and braced by adjusting the extension-legs *L*. The drill *C* is adjusted along the revolving arm *B* until the desired distance from the column *A* to give the required diameter of stone is obtained, and is then properly secured thereto. Power is then applied to move the drill-piston, which, as it rises through the medium of rod *D* and cord *E*, applies power to the pulley *G*. Pulley *G* in this movement clutches and rotates shaft *g* and its worm *H*, which as it gears with the fixed gear-wheel *I* causes the rotary movement of the arm *B* a short distance. When the piston of drill *C* descends, the pulley *G* rotates in reverse direction, moving loosely on the shaft *g*, and the arm *B*, whether held by a reverse clutch or otherwise, remains stationary during the operation of the drill. When the drill next rises and falls, the above operations are repeated, and thus the drill is advanced in a curved path until the circle is completed.

Having thus set forth the nature, operation, and advantages of my invention, what I claim, and desire to secure by Letters Patent, is—

1. In a machine for quarrying grindstones and like circular articles, the combination of a center post or column, a revolving drill-carrier journaled thereon, said post and carrier being provided with intermeshing gear, a reciprocating drill mounted on the carrier, and connections between the drill and gearing for transmitting the motion of the former to the latter, substantially as shown and described.

2. In a machine for quarrying grindstones and like circular articles, the combination of a center post or column, a revolving drill-carrier journaled thereon, said post and carrier being provided with intermeshing gear, a reciprocating drill mounted on the revolving drill-carrier, a clutch located upon the

operating gear-shaft, and connections between the drill and clutch for operating the latter, substantially as shown and described.

3. In a machine for quarrying grindstones and like circular articles, the combination of a center post having a gear or worm wheel secured thereto, a revolving tool-carrier journaled on the center post, a worm, and a clutch-pulley journaled on the revolving tool-carrier, a reciprocating drill, and a band or cord for imparting the movement of the drill to the clutch-pulley, substantially as and for the purposes specified.

4. In a machine for quarrying grindstones and like circular articles, the combination of the center post or column, *A*, having the worm-wheel *I* secured thereto, the revolving tool-carrier *B*, journaled on the column *A*, the worm-wheel *H*, having the clutch-pulley *G*, and journaled on the revolving tool-carrier, the reciprocating drill, the rod *D*, attached thereto, the guide-pulleys *F F*, and the rope or band *E*, substantially as and for the purposes specified.

5. In a machine for quarrying grindstones and like circular articles, the combination of a center post, *A*, the base *Y*, having a central perforation through which the post passes, the wedges *w*, the set-screws *S S*, and the revolving drill-arm journaled on the center post, substantially as shown and described.

6. In a machine for quarrying grindstones and like circular articles, the combination of a center post, *A*, the base *Y*, having a central perforation through which the post passes, the extension-legs *L L*, the wedges *w*, the set-screws *S S*, and the revolving drill-arm journaled on the center post, substantially as shown and described.

In testimony whereof I affix my signature, in presence of witnesses, this 28th day of July, 1884.

MICHAEL J. O'CONNOR.
